UNITED STATES PATENT OFFICE.

KENNETH RUSHTON, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

SHIFTING MECHANISM FOR VALVE-GEAR.

1,141,008.

Specification of Letters Patent. Patented May 25, 1915.

Application filed March 11, 1915. Serial No. 13,770.

To all whom it may concern:

Be it known that I, KENNETH RUSHTON, a citizen of the United States, residing in Philadelphia, Pennsylvania, have invented 5 certain Improvements in Shifting Mechanism for Valve-Gears, of which the following is a specification.

This invention relates to certain improvements in the shifting mechanism for valve 10 gears of the type known as "Walschaerts valve motion."

The object of the invention is to construct the shifting mechanism in such a manner that it can be applied to any type of locomotive, particularly the type in which the boiler is set low, without disturbing the alinement. This shifting mechanism can be used in connection with the standard type 15 of valve gear without altering the position 20 of the main parts thereof.

In the accompanying drawing: Figure 1, is a side view of sufficient of a locomotive to illustrate my invention; and Fig. 2, is a perspective view of the shifting mechanism.

Referring to the drawing, 1 is the cylinder of the locomotive.

2 is the valve chest.

3 is the boiler.

4 is the main driving wheel, shown by 30 dotted lines.

5 is a pin on the wheel or on a crank secured to the axle 6.

7, 7 are the guides for the cross head 8, which is attached to the piston rod 9 in the 35 usual manner.

10 is a valve stem attached to a block 11 to which the lever 12 is pivotally connected. The long arm of the lever is connected by a 40 link 13 to the cross head 8, while the other arm of the lever is connected to a radius bar 14 carrying a block 15 which is vertically adjustable in the segment 16, which is pivoted at 16^a to a beam 23 secured to the main frame 24 of the locomotive. An arm 17 on 45 the lower end of this segment is connected by a rod 19 to a pin 20 on the crank 21 secured to the pin 5 on the driving wheel 4. Heretofore, when the valve gear was used on a locomotive having a low set boiler, the 50 shaft would have to be distorted in order to clear the boiler.

22 is the reverse shaft adapted to bearings 23^a on the beam 23, and projecting from this reverse shaft is an arm 22^a to

which is attached the operating rod 25 leading to the cab of the locomotive. On each end of the reverse shaft 22, as clearly shown in Fig. 2, is a lifting arm 26, and mounted in bearings 27 at each side of the locomotive, in the present instance above the bottom line 60 of the boiler, is an arm 28 having trunnions 29 adapted to the said bearings 27 and, in the present instance, this arm is forked and two links are connected to the arm. One link 30 is attached to the outer end of the 65 arm 26 and the other link 31 is attached to the bar 14, which is also forked, in the present instance, to span the segment 16. The arm 28 and the arm 26 may be of any length desired and the links 30 and 31 may 70 be connected to the arm 28 at any point desired.

By this construction, it will be seen that the pivoted member 28, which is connected to the bar 14 by the link 31, is pivotally 75 mounted at a point above the bottom line of the boiler. The link 30 can be of any length desired so as to allow the reverse shaft 21 to pass under the boiler and clear of the other elements of the locomotive. 80

I claim:

1. The combination of a reverse shaft; an arm thereon; means for turning the reverse shaft; an arm pivoted to a fixed point above the reverse shaft; a link connecting the two 85 arms; a radius bar; a link connecting the radius bar with the said pivoted arm; a cross head and a valve rod connected to the bar; and a segment for controlling the movement of the bar and regulating the 90 movement of the valve rod.

2. The combination in shifting mechanism for valve gears, of a reverse shaft extending under the boiler of a locomotive; means for turning said shaft; a lifting arm 95 on the shaft at each side of the locomotive; an arm pivoted at a point above the reverse shaft at each side of the locomotive; a link connecting each arm with the lifting arm on the reverse shaft; a second link attached 100 to each of the pivoted arms and to the radius bar pivotally mounted on each side of the locomotive; a segment controlling the movement of the bar; and means connecting the bar with a valve rod and a cross head 105 at each side of the locomotive.

3. The combination in shifting mechanism for locomotive valve gears, of the main

frame of a locomotive; a bearing frame secured thereto at each side of the locomotive; a boiler; a reverse shaft extending under the boiler and mounted in bearings on the said bearing frame; a segment pivoted to each bearing frame; means for moving said segment from a driving wheel; a bar at each side controlled by the above mentioned segments; a cross head and a valve rod; a lever connecting the cross head, valve rod and radius bar; an arm at each side of the locomotive mounted in the bearing frames above the reverse shaft; an arm at each end of

the reverse shaft; links connecting the said arms with the last mentioned arms; and 15 links connecting the radius bars with the last mentioned arms at a point beyond the first mentioned links.

In testimony whereof, I have signed my name to this specification, in the presence of 20 two subscribing witnesses.

KENNETH RUSHTON.
